UNITED STATES PATENT OFFICE.

JOHN M. McCARTHY, OF CHICAGO, ILLINOIS.

LICENSE-INDICATOR.

1,336,706.

Specification of Letters Patent.

Patented Apr. 13, 1920.

Application filed August 26, 1918. Serial No. 251,435.

To all whom it may concern:

Be it known that I, JOHN M. McCARTHY, a citizen of the United States, residing at Chicago, in the county of Cook and State 5 of Illinois, have invented certain new and useful Improvements in License-Indicators, of which the following is a specification.

This invention relates to license indicators for motor cars and like vehicles, and its object is to provide an indicator which renders the license number clearly legible at a considerable distance by night or by day.

Another object of the invention is to render the indicator readily applicable and 15 adjustable to license plates of varying lengths, so as to continue in use as new numbers are obtained from year to year.

A still further object is to embody in the indicator a tail-light element as a substitute 20 for the usual tail lamp.

With the above objects in view, the invention consists in a novel combination and arrangement of parts to be described and claimed hereinafter, reference being had to 25 the accompanying drawing, in which—

Figure 1 is an elevation of the indicator, as viewed from the rear of the vehicle;

Figs. 2 and 3 are, respectively, sectional views taken on the lines 2—2 and 3—3 of 30 Fig. 1; and

Fig. 4 is an elevation of the indicator, as adjusted for a small license number.

Referring specifically to the drawing, the indicator is in the form of an elongated casing and made of two telescopically slideable sections 5 and 5^a. These are of heavy sheet metal and have, respectively, top walls 6 and 6^a, bottoms 7 and 7^a, and end walls 8 and 8^a. The front of the casing is open, except for 35 inturned flanges 9 bent from the top walls 6 and 6^a and the bottoms 7 and 7^a. While at one end of the flanges 9 the end wall 8^a extends to meet the latter, and form a closure for the casing, the end wall 8 terminates 40 short of the opposite end of said flanges, so as to permit two plates 10 and 11 to be inserted along the inner surface of the flanges.

The plate 10 is positioned next within the flanges 9, and is of black painted metal, 45 stenciled with the license number at 12 and with the state and year to which the license relates at 13. The plate 11 is positioned immediately behind the plate 10, and is of heavy opal glass. The end walls 8 and 8^a 50 of the casing have vertical inner flanges 14

positioned immediately behind the plate 11, these serving to preserve the position of the plates 10 and 11, and to prevent the latter from backing into the casing.

The plates 10 and 11 are moved into the 60 position described by being slid from that end of the casing corresponding to the wall 8. The latter carries a spring clip 15, pivoted at 16, which may be swung to abut the exposed ends of the plates 10 and 11, 65 after the latter have been slid into place, to prevent the plates from sliding out of place. The plates may, however, be easily removed by manually drawing the clip 15 out of the way.

The indicator has an illuminating element 70 in the form of an electric lamp 17, whose socket 18 extends through registering apertures 19 in the bottom sections 7 and 7^a of the casing, and takes a nut 20 for the purpose of securing the sections of the casing 75 at the bottom. The top walls 6 and 6^a are similarly apertured to receive a bolt 21 and nut 22, so that a fastening may also be provided thereat.

With the indicator in operation during 80 the day, the white numbers of opal glass will be easily legible at a considerable distance as against the black stencil plate 10; and at night, the translucent property of 85 the opal glass, with the aid of the electric lamp 17 within the casing, will render the numbers distinct and sufficiently bright to be read from afar.

The glass plate 11 is made with a portion—integral or separate—tinted red, said portion being located behind the state and year indicia 13. This feature will render 90 the corresponding portion of the indicator red at night, and will perform the function 95 of the usual tail lamp, dispensing with the latter.

As license plates are made of various 100 lengths, in proportion to the length of the license number, it will be apparent that the telescopic construction of the casing will 105 adapt the latter to such plates without alteration. Thus, in Fig. 4 is shown an indicator contracted in proportion to a three-figure license number. The adjustment of the electric lamp 17 is adapted to that of the casing by the provision of a series of apertures 23 in the bottom 7 of the casing section 5 similar to the aperture 19. The apertures 23 are normally closed by partly perforated 110

disks 24, any of which may be easily removed to permit the lamp to be adjusted in the resulting aperture, when the casing is contracted. The disks 24 may be removably secured and adapted for replacement in any suitable manner. The top wall 6 of the casing section is also provided with a series of closed apertures (not shown) for the adjustment of the bolt 21 in manner similar to 10 that of the lamp, as described.

In order that the sections 5 and 5^a of the casing may have sufficient rigidity at any position adjusted to withstand shocks and vibration, the top walls 6 and 6^a, as well as 15 the bottoms 7 and 7^a, are pressed with a series of concavo-convex indentations 25, which are designed to interfit snugly, and to hold the superposed sheets firmly together. It will be understood that the arrangement 20 of the indentations 25 will not interfere with the telescoping action of the casing sections, as the metal is sufficiently tensile to yield during such action.

While the preferred form of the invention 25 has been described, it will be evident that many changes and refinements may be made in the structure without departing from the scope of the invention.

I claim:—

1. A license indicator comprising a sheet 30 material casing formed of telescopically 35 slidable sections, one side of the casing being open to receive a license plate and having inturned flanges to retain the latter, and interfitting indentations made in the superposed walls of the casing sections for holding the same together rigidly at various telescopically adjusted positions thereof.

2. A license indicator comprising a sheet material casing formed of telescopically 40 slidable sections, one side of the casing being open to receive a license plate and having inturned flanges to retain the latter, interfitting indentations made in the superposed walls of the casing sections for holding the same together rigidly at various telescopically adjusted positions thereof, an illuminating element incorporated in the bottom casing sections, and a fastening element incorporated in the top casing sections, 45 these elements serving to form securing means for the casing sections at various telescopically adjusted positions thereof.

In testimony whereof I affix my signature.

JOHN M. McCARTHY.
